ELECTRIC WAVE FILTER

Douglas Cecil Rogers, London, England, assignor
to Standard Telephones and Cables Limited,
London, England, a British company

Application October 14, 1942, Serial No. 462,026
In Great Britain October 15, 1941

7 Claims. (Cl. 178—44)

1

The present invention relates to filtering arrangements for ultra-high-frequency electric wave transmission or generating apparatus, and in particular to arrangements for preventing leakage of the high frequency into the power supply leads.

One of the problems presenting great difficulty in the design of apparatus for use on centimetre range wavelengths, is that of providing adequate filtering for the supply leads.

One method, described in British patent specification No. 541,380, which has been found effective, is the use of an arrangement resembling a condenser having input and output leads at opposite ends of each foil. The condenser then becomes a four terminal network, and takes the form of a transmission line of low characteristic impedance. By this means the residual lead inductance found in the more conventional type of condenser is made to contribute to the desired effect, instead of being detrimental.

The present specification describes a method whereby the effectiveness of the arrangement described above can be considerably increased. The method is suitable for use at wave lengths between about 1 centimetre and 1 metre.

According to the invention, there is provided an electric wave filter for ultra high frequencies comprising a conductor in the form of an elongated thin metallic sheet divided into alternate wide and narrow portions arranged in close proximity to, but electrically insulated from, another conducting sheet.

According to another aspect, the invention comprises an electric wave filter for ultra-high frequencies comprising a series of tandem connected transmission lines of alternate low and high image impedance, each of the said lines comprising a pair of thin flat parallel sheet conductors arranged in close proximity to, but electrically insulated from, one another.

The invention will be better understood by reference to the following detailed description and to certain figures on the accompanying drawing in which:

Figs. 1A, B, and C, show examples of the forms of transmission line conductors according to the invention; and Fig. 2 shows a filter circuit (not referred to in this specification);

Fig. 3 shows a portion of the conductor of Fig. 1A to define an elementary section of the filter;

Fig. 4 shows an equivalent block schematic diagram of the elementary section of Fig. 3; and

Fig. 5 is a sectional end view of the conductors forming the filter.

2

The arrangement described in specification No. 541,380 usually takes the form of a thin strip of copper or other metal clamped between two earthed copper plates, and insulated with thin sheets of mica, or other dielectric material. The method of increasing the effectiveness of such a filter according to the present invention is to use a metal strip cut to a particular shape such as is shown in Fig. 1A, or an equivalent conductor, in place of the plain rectangular strip previously used. It will be seen that the strip is thus divided into alternate wide and narrow sections, corresponding to short lengths of transmission line of low and high characteristic impedance respectively.

This arrangement can be shown from well known transmission theory to have properties similar to those of wave filters, in so far as it exhibits pass bands and attenuating bands, which 20 can be made to cover given frequency ranges by suitable dimensioning of the conductor strip shown in Fig. 1A. A wide variety of shapes is, however, possible, two other examples being shown in Figs. 1B and 1C, which produce substantially the same result as Fig. 1A. Fig. 1C is a convenient form because it enables the total length of the conductor strip to be reduced.

The chief advantage of the arrangement of the invention lies in its simple construction. The 30 construction of filters using the same underlying principle has previously been described, such filters being of the coaxial line type: in this case the necessary changes of impedance are brought about by cylindrical metal blocks threaded on to 35 the centre conductor.

By suitably proportioning the lengths and impedances of the various sections of the strip, it is possible to produce characteristics similar to those of conventional multiple band-pass or band 40 elimination filters.

Fig. 3 shows a portion of a strip similar to Fig. 1A comprising two wide sections and one narrow section between them. If the wide sections be supposed to be bisected by the dotted lines XX 45 and YY, then the whole strip may be regarded as made up of a number of elementary sections like that comprised between the lines XX and YY, joined in tandem. These sections will be all equal and symmetrical.

The strip may be made into a filter by mounting it parallel to a plain metal strip or to another strip of the same form, with suitable insulation between. This filter can then be regarded as made up of a number of tandem connected 55 transmission lines of alternatively high and low

impedance, which may be divided into a series of symmetrical sections each of which corresponds to the portion between the lines XX and YY in Fig. 3.

Fig. 4 shows a block schematic circuit of the equivalent electrical network of the filter corresponding to this portion of the strip. It comprises two symmetrical networks A and C each corresponding to half a wide portion and a third symmetrical network B connected between them and corresponding to a whole narrow portion. A and C have image impedance Z_1 and image transfer constant $\theta_1/2$, and B has an image impedance Z_2 and image transfer constant θ_2 . The image impedance of the combination representing the elementary section is Z and the image transfer constant is ϕ .

Assuming that the transmission lines do not themselves introduce any transmission loss, or in other words that θ_1 and θ_2 have no real components, it can easily be shown that

$$\cosh \phi = \cos \theta_1 \cos \theta_2 - \frac{1}{2} (Z_1/Z_2 + Z_2/Z_1) \sin \theta_1 \sin \theta_2 \quad (1)$$

The pass frequency bands are obtained for those values of θ_1 and θ_2 for which $\cosh \phi$ lies between +1 and -1. In the suppression bands, the attenuation constant β is given by:

$$\cosh^2 \beta = [\cos \theta_1 \cos \theta_2 - \frac{1}{2} (Z_1/Z_2 + Z_2/Z_1) \sin \theta_1 \sin \theta_2]^2 \quad (2)$$

If it be assumed that the electrical length of the elementary section XX, YY is fixed, or in other words that $\theta_1 + \theta_2 = 2\theta$, then

$$\beta = \cosh^{-1} [(1 + \frac{1}{2} (Z_1/Z_2 + Z_2/Z_1)) \sin^2 \theta - 1] \quad (3)$$

It can be shown that β is a maximum when $\theta - \theta_1 = n\pi/2$. The most useful value of n is zero so that $\theta = \theta_1 = \theta_2$, and in these circumstances the maximum value of β occurs when $\theta = (2n+1)\pi/2$, and is given by

$$\beta_{\max} = \cosh^{-1} \frac{1}{2} (Z_1/Z_2 + Z_2/Z_1) \quad (4)$$

It is, however, of more practical value to determine the maximum attenuation per unit physical length of the strip than per elementary section. The attenuation per unit length is given by:

$$\frac{\beta}{\theta} = \frac{\cosh^{-1} [(1 + \frac{1}{2} (Z_1/Z_2 + Z_2/Z_1)) \sin^2 \theta - 1]}{\theta} \quad (5)$$

The maximum value of β/θ may be determined graphically for various values of Z_2/Z_1 . For example, if $Z_2/Z_1 = 10$, which is a convenient practical value, it follows that

$$\frac{\beta}{\theta} = \frac{\cosh^{-1} (6.05 \sin^2 \theta - 1)}{\theta} \quad (6)$$

and this is a maximum when $\theta = 55^\circ$ approximately.

In this case the attenuation per section, which is given by $\cosh^{-1} (6.05 \sin^2 \theta - 1)$, will be about 15.7 db. If λ is the wave length, and x is the physical length of the elementary section, Fig. 3, then:

$$x/\lambda = 2\theta/2\pi = \theta/\pi \quad (7)$$

Thus if $\theta = 55^\circ$ and $\lambda = 10$ cm., then $x = 3.95$ cm., and a filter with ten elementary sections would have an attenuation of 157 db and would be just over a foot long.

It can be shown that when $\theta = \theta_1 = \theta_2$, the image impedance Z of the element is given by

$$\left(\frac{Z}{Z_1}\right)^2 = \frac{(Z_2/Z_1 + 1) \cos \theta + Z_2/Z_1 - 1}{(Z_2/Z_1 + 1) \cos \theta - Z_2/Z_1 + 1} \quad (8)$$

Taking $Z_2/Z_1 = 10$ and $\theta = 55^\circ$ as before, it follows that

$$\frac{Z}{Z_1} = 2.385j$$

When designing a filter to meet certain given requirements, the preferred procedure is to employ sections having maximum attenuation per unit physical length, and to choose $\theta = \theta_1 = \theta_2$. The maximum value of Z_2/Z_1 which can reasonably be used will be decided from practical considerations of the construction of the filter and will depend among other things on the amount of current the filter must be designed to carry. The corresponding attenuation per section is determined by finding from Equation 5 for the given value of Z_2/Z_1 the corresponding value of θ for maximum attenuation per circuit length and obtaining the corresponding value of β per elementary section from Equation 3. This can best be done graphically by constructing a curve relating β to Z_2/Z_1 from these two equations. This will give the number of sections required for any given total attenuation. The physical length x of the elementary section depends on the maximum wave-length to be attenuated. If this is λ , then from Equation 7 the length x may be obtained by substituting the previously found value of θ . Then $x/2$ gives the length of the wide and narrow portions of the strip. A graph can be constructed if desired to obtain x directly from Z_2/Z_1 , for the assumed attenuation conditions.

It can be shown that the attenuation for a certain band of wave-lengths less than the chosen maximum wave-length will be equal to or greater than that of the maximum wave-length; and that the width of this band increases as Z_2/Z_1 is increased.

In the above explanation it has been assumed that the effective dielectric for the section XX, YY is air. If, as will generally be the case, the strips are insulated with a material having a dielectric constant K , then the length x determined from Equation 7 should be divided by $\sqrt{K}$, so that the insulating material is an advantage because it makes the filter shorter.

It will be evident that the narrow portions of the filter may be bisected instead of the wide portions to form the elementary section. The discussion above will not be affected except that at the ends of the filter (assuming it is terminated in a half section) the image impedance Z will be given by an equation the same as (8) except that the left hand side is replaced by

$$\left(\frac{Z}{Z_2}\right)^2$$

By using a strip having the form of Fig. 1C, the filter is shortened, as already explained; and if the clearance between the wide and narrow portions is not so small that the capacity between them becomes appreciable, the formulae explained above will be found to hold with sufficient accuracy.

An alternative improved method of construction of the filter of the invention is to deposit the metal directly on one or both sides of the dielectric sheet. Thus, copper may be plated directly on to mica, for example, by first spraying thereon through a stencil a colloidal graphite solution such as that known by the registered trade-mark "Aquadag" to form a conducting base. Alternatively silver may be baked on to mica in a manner similar to that used in the construction of silver

5

ceramic condensers. In this case, the silver paste may be applied by means of a rubber stamp.

Experimental filters have been made by this method, and it is found that the thin layer of metal so formed is quite capable of carrying direct currents in the order of one ampere. A further advantage is that the metal is in more intimate contact with the dielectric, thus increasing the capacity per unit length, thereby giving a lower input image impedance (a desirable feature when filtering from high impedance sources).

The filter may be constructed in a form balanced or unbalanced to ground. In the first case it may consist of two identical strips of any of the forms shown in Figs. 1A, 1B or 1C, (or any other like forms exhibiting wide and narrow portions) arranged to register on either side of an insulating strip. In the second case, when one of the conductors will be at ground potential, this conductor would preferably be a plain rectangular strip of area sufficient to cover the formed strip; and could conveniently be, for example, part of the screen of the apparatus in which the filter is to be mounted. In this case, for example, a thin strip of insulating material having the formed 20 conductor deposited on one side would be fixed to the screen, suitable input and output terminals in contact with the metal layer being provided at the ends of the strip; a suitably insulated plain earthed metal strip is preferably mounted also 30 outside the conductor formed on the dielectric to serve as a screen. Allowance must of course be made for this extra strip as it will roughly halve the impedance of the filter.

It will be clear that the strips may be arranged 35 in various other ways.

What is claimed is:

1. An electric wave filter for ultra high frequencies comprising a first conductor in the form of an elongated thin metallic sheet divided into 40 alternate wide and narrow portions all of substantially the same physical length, a second conductor in the form of a sheet, and means for insulatingly spacing the said first and second conductors from one another.

2. An electric wave filter for ultra high frequencies comprising a series of tandem connected

6

transmission lines all of substantially equal electrical length and alternately of high and low image impedance, the said lines each comprising a pair of thin, flat, parallel sheet conductors in close proximity, but electrically insulated.

3. An electric wave filter for ultra high frequencies comprising a first conductor in the form of an elongated thin metallic sheet divided into alternate rectangular wide and narrow portions all of substantially the same physical length, a second conductor in the form of a sheet, and means for insulatingly spacing the said first and second conductors from one another.

4. An electric wave filter for ultra high frequencies comprising two conductors each in the form of an elongated thin metallic sheet divided into alternate rectangular wide and narrow portions all of substantially the same physical length, and means for insulatingly spacing the said conductors from one another with correspondingly shaped portions in registration with one another.

5. A filter as claimed in claim 3 in which the said wide and narrow portions are symmetrically arranged with respect to the centre line of the sheet.

6. An electric wave filter for ultra high frequencies comprising an elongated metallic sheet conductor in the form of rectangular portions spaced apart, and narrow portions connecting diagonally oppositely facing corners of the said rectangular portions, a second conductor in the form of a sheet, and means for insulatingly spacing the said first and second conductors from one another.

7. An electric wave filter for ultra high frequencies comprising a series of tandem connected transmission lines of substantially equal electrical length and of alternate high and low image impedance, the said lines each comprising a pair of thin flat parallel sheet conductors in close proximity but electrically insulated and of such electrical length in relation to the ratio of the said image impedance as to give a maximum attenuation per unit physical length of the said 45 filter.

DOUGLAS CECIL ROGERS.
